UNITED STATES PATENT OFFICE.

HERMAN C. PRIEBE, OF BLUE ISLAND, ILLINOIS.

DRAFT-GEAR.

1,253,187.

Specification of Letters Patent.

Patented Jan. 8, 1918.

Application filed July 9, 1917. Serial No. 179,552.

To all whom it may concern:

Be it known that I, HERMAN C. PRIEBE, a citizen of the United States, residing at Blue Island, in the county of Cook and 5 State of Illinois, have invented a certain new and useful Improvement in Draft-Gears, of which the following is a full, clear, concise, and exact description.

My invention relates to railroad cars and 10 has for its object the provision of an improved draft gear structure and particularly to the means for assembling the same in a car structure. My invention is of particular service in the application of the draft 15 gears to cars having wooden center sills.

My invention, in some of its aspects, is an improvement upon the draft gear disclosed in my Patent 799,263, dated September 12, 1905.

20 In another of its aspects the invention contemplates means whereby a given draft gear is adaptable to cars whose body bolsters are of different widths.

My invention in all of its aspects will be 25 fully described in connection with the accompanying drawings showing the preferred embodiment thereof and in which Figure 1 is a plan view, partially in section; Fig. 2 is a view on line 2—2 of Fig. 1; Fig. 3 is 30 a view in elevation of one of the draft bars that enter into my preferred construction; Fig. 4 is a view on line 4—4 of Fig. 2; Figs. 5, 6 and 7 illustrate details of construction showing an element whereby the draft gear 35 may be adapted to cars having body bolsters of different widths; and Fig. 8 is a perspective view of a part shown in Figs. 5, 6 and 7.

Like parts are indicated by similar characters of reference throughout the different figures.

A portion of a car whose underframe is constructed mainly of wood is illustrated. The car floor *a* is supported upon the 45 wooden center sills *b*, these center sills extending from end to end of the car in accordance with common practice. These center sills are supported upon body bolsters *3* which in turn are supported upon suitable 50 trucks, not shown, all as will be understood by those skilled in the art. At each end of the car there is a suitable draft gear, to the form of which my invention is not to be limited. The draft gear at one end of 55 the car is shown in Figs. 1 and 2 and will be generally described. This draft gear includes a coupler *1* having a shank *2* which is connected with the yoke *2* below the center sills *3*. An outer follower *4* is at the front end of the yoke and an inner follower *5* is at the rear end of the yoke, the outer follower being capable of rearward movement when the coupler is moved inwardly and the inner follower being capable of outward movement when the coupler is moved outwardly. Coiled spring sets *6*, *7* and *8* are interposed between the followers *4* and *5* to resist the motion of each toward the other, the followers projecting beneath and across the center sills *b*. These followers project through cheek plates *9* that are riveted to the inner faces of the draft bars *10*. The cheek plates are provided with slots *11* that are co-extensive with the slots *12* in the draft bars, the followers being adapted to 70 operate longitudinally of the car in these slots. The draft bars *10* have top flanges *13* and bottom flanges *14*, the draft bars then being in the nature of channel irons. The inner and bottom faces of the center sills, at 75 each end of the car structure, are lined by angle bars *15*. The bottom flanges of these angle bars *15* rest upon the top flanges *13* of the draft bars *10* and are riveted thereto by rivets *16*. The elongated bolts *17* pass 80 vertically through the center sills *b*. The outer end of each draft bar *10* is riveted at 85 *18* to a cast buffer block *19*. This buffer block is reinforced by the end sill *20* which in turn is reinforced by the angular bracket *21* riveted upon each center sill angle iron *15* and having a branch engageable with the end sill. The inner end of each draft bar 90 has riveted thereto an angular bracket *22* having a branch that engages the outer face *95* of the adjacent body bolster *3*. By this arrangement the body bolster receives the buffing shocks to which the draft bars *10* are subject, the body bolster in turn being reinforced by a plate *23* secured to the bottom of each angle bar *15* and engaging the inner face of the bolster. The draft bars *10* thus terminate at the outer face of the adjacent body bolster *3* but the angle bars *15* are desirably continued inwardly beyond 100 the plates *23* to enable these plates to be attached thereto and for the purpose of securing thorough reinforcement of the bars and the center sills where the draft rigging is disposed. The top margins of the angle 105 bars *15* are desirably continued inwardly beyond the plates *23* to enable these plates to be attached thereto and for the purpose of securing thorough reinforcement of the bars and the center sills where the draft rigging is disposed. The top margins of the angle 110

bars 15 are desirably provided with angle brackets 15¹ to reinforce said angle bars in the region of the body bolster.

These body bolsters vary in horizontal width as illustrated in Figs. 5, 6 and 7, the body bolster shown in Fig. 5 being wider than the body bolster shown in Fig. 6 while the latter body bolster is wider than the body bolster illustrated in Fig. 7. The plate 10 or block 23 shown in detail in Fig. 8 is provided with rivet holes 24, 25, 26 and 27 for the reception of rivets 28 that pass through other rivet holes in the angle bars 15 that register with the holes in the plate 23. The 15 holes through the plate 23 are arranged at the corners of a square, the sides of this square being parallel with the adjacent sides of the rectangular plate 23. The portions of the space between these squares upon the 20 different sides thereof differ in width, whereby the space between the brackets 22 and the plates 23 may be varied to suit the horizontal width of the body bolster of the particular car to which the draft gear is to 25 be applied. The holes 24, 25 are nearer the edge of the plate 23 adjacent thereto than the holes 25, 26 are to the edge of the plate 23 adjacent thereto, these latter holes being nearer the edge of the plate or block 23 adjacent thereto than the holes 24, 27 are to the edge of the plate 23 adjacent thereto. When the widest bolster 3, shown in Fig. 5, is to be reinforced by the plates 23 said plates are secured to the bottoms of the angle bars 15 30 said plates are disposed with the holes 24, 25 adjacent the body bolster. When the narrower bolster, shown in Fig. 6, is to be reinforced by the plates 23 said plates are disposed with the holes 25, 26 adjacent the body 35 bolster. When the narrowest bolster, shown in Fig. 7, is to be reinforced by the plates 23 said plates are disposed with the holes 24, 27 adjacent the body bolster. It is not practical to provide new holes in the body bolsters 40 and angle irons since the changes are generally made where there are no drill presses or punching machines available. By providing the blocks 23 with the holes arranged therein as described all the necessary punching may be performed in the shop upon 45 these plates which are shipped loose to the places where they are to be applied, it being very convenient for the workmen to place the blocks upon the center sills in positions 50 that will enable them to engage the bolsters. This is the preferred way of making the plates 23 adjustable longitudinally of the center sills to vary the spaces between them and the draft bars 10 to accommodate body 55 bolsters of different widths but I do not

wish to be limited to this arrangement and while these plates are preferably connected with the center sills by being connected with the bottom flanges of the angle bars 15, I do not wish to be limited to this method of 65 adjustably securing these plates to the center sills. It is to be understood that the plates 23 serve as a medium for the center sills and the body bolster whereby forward draft is exerted upon the body bolster, the draft 70 bars 10 and the brackets 22 secured thereto and forming parts thereof transferring buffing strains to the body bolster.

As I have illustrated my invention it will be observed that the space between the draft 75 bars 10 is larger than the space between the center sills b whereby I am enabled readily to accommodate the cheek plates 9 between the draft bars 10 and the coupler structure between the cheek plates. The offset relation of the bars 10 and 15 enable me to provide the increased space between the bars 10 for the accommodation of the cheek plates and coupler structure. The adjacent flanges 80 of the bars 10 and 15 employed in conjunction with each center sill serve greatly to reinforce the structure. Moreover, the spacing between the wooden center sills b varies with different makes of cars, on which account the spacing between the draft bars 10 85 may be made uniform although the width of the free space between the center sills, inclusive of their enlargements 15, may vary. 90

While I have herein shown and particularly described the preferred embodiment of 95 my invention I do not wish to be limited to the precise details of construction shown as changes may readily be made without departing from the spirit of my invention, but having thus described my invention I claim 100 100 as new and desire to secure by Letters Patent the following:—

A car structure including center sills; a body bolster; draft bars engaging the outer face of the body bolster; blocks for engaging the inner face of the body bolster and having holes therethrough located at unequal distances from the edges of the blocks, there being holes in the center sill structure corresponding to the holes in the blocks, 110 the holes in the blocks and center sill structure registering in various positions of the blocks whereby the spaces between the blocks and the draft bars may be varied; fastening means passed through the registering holes; and a draft gear carried by the draft bars. 115

In witness whereof, I hereunto subscribe my name this 23rd day of June A. D., 1917.

HERMAN C. PRIEBE.
